United States Patent Office

Des. 176,887
Patented Feb. 7, 1956

176,887

ELECTRIC KNIFE SHARPENER

Fred C. Schwanek and Jack Morgan, Chicago, Ill., as
signors to Dormeyer Corporation, Chicago, Ill., a cor-
poration of Illinois

Application November 12, 1954, Serial No. 33,078

Term of patent 14 years

(Cl. D37—1)

Fig. 4.

Fig. 5.

Fig. 1 is a front elevational view of an electric knife sharpener showing our new design;

Fig. 2 is an end elevational view thereof;

Fig. 3 is an elevational view of the other end thereof;

Fig. 4 is a rear elevational view thereof; and

Fig. 5 is a top plan view thereof.

The dominant features of our design reside in the portion shown in full lines.

We claim:

The ornamental design for an electric knife sharpener, as shown and described.
